(57) **CLAIM**

We claim the ornamental design for a beverage can insulator, as shown and described.

DESCRIPTION

FIG. 1 is a perspective view of a beverage can insulator, showing our new design;

FIG. 2 is a front elevational view thereof, the rear elevational view being a mirror image thereof;

FIG. 3 is a left-side elevational view thereof, the right-side elevational view being a mirror image thereof;

FIG. 4 is a top plan view thereof;

FIG. 5 is a bottom plan view thereof;

FIG. 6 is an exploded top perspective view thereof; and,

FIG. 7 is an exploded bottom perspective view thereof.

The broken lines showing a can in FIGS. 6 and 7 depict environmental matter and form no part of the claimed design.
